UNITED STATES PATENT OFFICE.

JAMES S. B. ANDERSON, OF NORFOLK, VIRGINIA.

SHIP'S PROPELLER.

SPECIFICATION forming part of Letters Patent No. 366,550, dated July 12, 1867.

Application filed March 29, 1857. Serial No. 232,876. (No model.)

To all whom it may concern:

Be it known that I, JAMES S. B. ANDERSON, a citizen of the United States, residing at Norfolk, in the county of Norfolk and State of Virginia, have invented a new and useful Improvement in Ships' Propellers, of which the following is a specification, reference being had to the accompanying drawings.

This invention relates to improvements in the class of propellers for ships denominated "vibrating," which will be hereinafter more particularly described, and pointed out in the claims.

In the drawings forming part of this specification, Figure 1 is a vertical longitudinal section of the propeller. Fig. 2 is a plan view of Fig. 1. Fig. 3 is a vertical longitudinal section of the after part of a vessel with the propeller represented in elevation. Fig. 4 is a plan view of two cylinders, showing the vibrating bar to connect with the piston-rods.

A is a chamber, which is to be placed in the lower part at the stern of a vessel designed to be propelled by this invention. This chamber is to be made of metal plates and to be water-tight, except where the proper openings are designed to be formed in it—viz., in the rear end, A', and in the bottom at the front end at A''. The opening in the rear end can be closed by a vertically-sliding door, B, and the front opening, A'', can be closed by a horizontally-sliding door, C. The purpose of these openings and their closing doors will be hereinafter more fully described.

When two propellers are to be used, each one has its separate chamber constructed as above described, one of which is placed on each side of the keel and stern-post of the vessel. On each side of the interior of the chamber, about midway, is a horizontal groove, α , extending the whole length of the sides. The front end of the chamber A is sloped at an angle of about forty-five degrees, and the opening A'' in the bottom of the chamber is immediately under this sloping end.

Within the chamber A is a sliding frame, D, made to fit snugly within the chamber, yet free to move to and fro therein. On the outside of the vertical sides of this frame D are tongues α' , which fit into the grooves α in the sides of the chamber A and act as guides to keep the frame D in its true line of motion. In the frame D

is pivoted to its vertical sides a bucket-board, E, formed wedge shape in vertical cross-section, having the thick edge at top, as seen in Fig. 1. This bucket is pivoted about one-third of its width from the top, so that when it is moved to the front there will be less lost motion than if hung from the top edge, and will be more quickly brought into action on the direct stroke for doing its work in either direction.

Within the bottom of the frame D is arranged a stop-bar, F, which has a slight vertical movement within its bearings to be controlled by a series of levers and cranks, which will be hereinafter explained.

The frame D is connected to the engine by means of the yoke G, placed about midway of the frame D, and in line with the groove α , so that the frame will have an even motion without binding within the chamber. The yoke G is attached directly in line to the end of the connecting-rod H, which passes through a packing-box, h, in the sloping front of the chamber A. The connecting-rod is a continuation of the piston-rod H of the direct-working cylinder I, which is properly placed upon its bed-plate and secured in the bottom of the vessel. The piston-rods H can be prolonged through the heads of the cylinders I I', and be connected together by a horizontally-vibrating rod, N, Fig. 4. This is when two propellers are used, one being on each side of the keel. The purpose of this connecting-rod N is as follows: When the piston-rod of engine I is on its return-stroke, the full force of the steam, having little work to perform, will draw the propeller-frame D backward with a jerk; but if connected with the piston-rod of the other cylinder, I', which immediately begins its forward stroke, the steam in cylinder I will thereby be aiding the steam in cylinder I' to drive the propeller, and so, vice versa, with cylinder I' to assist the work of cylinder I.

Attached to the connecting-rod or extension of piston-rod H, at any convenient point between the chamber A and the cylinder is a yoke, h', notched on the arch, having a shifting handle, i, on which handle is a connecting-rod, j, which passes through a packing-box, j', in the front end of chamber A, and it is connected to a bell-crank lever, k, which is pivoted to a rod, k', attached to the end of a

lever, k'' , pivoted at k''' on the side of the frame D. The loose end of lever k'' works in a slot in the cross-bar F, which is lifted to support the lower edge of the bucket E on either side 5 of it as the same may be used to "back" or "fill."

The position of the handle i in either of the notches in the yoke h' will indicate the position of the bar or stop F.

10 The frame D, with the bucket E, the lever k'' , bell-crank k , connecting-rods k' and j , and yoke h' , all being attached to the piston-rod H, are moved to and fro with it, and the adjustment of the bar or stop F is effected for 15 backing or going ahead without stopping the speed of the engine at all; hence this arrangement possesses great advantages over any other which is known to me.

The chambers A have their rear ends open 20 directly at the stern of the vessel on each side of the stern-post, so that the rudder O, Fig. 3, plays immediately between the streams of water forced from the buckets, so that the water is forced by one or the other directly upon the 25 rudder whenever the same is turned much to starboard or port side, thus aiding in steering of the vessel.

Should repairs be required at any time to the machinery in the chamber A, the vertical 30 slide B and horizontal slide C can be closed, so as to make chamber A water-tight. The slide C is moved by means of the screw c , bevelled gearing $c' c''$, operated by the hand-wheel c''' . The water which is in front of the bucket 35 is driven downwardly by the sloping roof of the chamber and out by the opening A" in

the bottom. There being a propeller on each side of the stern-post, they will work right and left, so that the momentum will always be kept up. As the propellers are worked directly from the piston, any length of stroke can be obtained by lengthening the cylinder, and thus gain greater speed. 40

I claim—

1. The combination of the vertically-adjustable stop-bar F within the frame D, operated by the lever k'' , pivoted on the frame D and the connecting-rod k' , the bell-crank k , connected to the adjusting-handle i by rod j , the notched yoke h' , and the piston-rod H of the 50 steam-cylinder, substantially as and for the purpose described. 45

2. The combination of the two sliding propeller frames and buckets having vertically-adjustable stop-bars within the frames, operated by levers, and connecting-rods attached to the piston-rods of two steam-cylinders and the vibrating bar, whereby the back and forward strokes are duly equalized, as described. 55

3. The chamber A, provided with the vertical-sliding door B and the horizontal-sliding door C, operated by means of the screw-rod c , revolved by the gearing c', c'' , and c''' , substantially as and for the purpose described. 60

In testimony that I claim the foregoing as 65 my own I hereto affix my signature in presence of two witnesses.

J. S. B. ANDERSON.
